UNITED STATES PATENT OFFICE.

EDWIN M. BASSLER, OF MILWAUKEE, WISCONSIN.

PROCESS AND APPARATUS FOR DRYING MATERIALS.

1,374,874.

Specification of Letters Patent.

Patented Apr. 12, 1921.

Application filed March 24, 1916, Serial No. 86,388. Renewed June 16, 1919. Serial No. 304,725.

To all whom it may concern:

Be it known that I, EDWIN M. BASSLER, a citizen of the United States, and resident of Milwaukee, in the county of Milwaukee and State of Wisconsin, have invented a new and useful Process of and Apparatus for Drying Materials, of which the following is a specification.

This invention relates to a process of and 10 apparatus for drying materials.

As my invention relates to a process of drying materials, the object of the invention is to provide an improved process of drying material by means of a forced circulation of hot air, whereby the drying of the 15 material may proceed as a continuous operation, and whereby, also, the material when thoroughly dried will be cooled to such an extent that it will be in condition for packing or storing.

As my invention relates to improved apparatus for practising said process, the object of the invention is to provide means for conveying the material to be dried in the 25 form of a layer of desired thickness, together with means for creating and passing a current of air heated to a desired high temperature consistent with safety from combustion, successively through said layer of material in the reverse direction to that in which said layer of material is being conveyed, said means for creating a current of air being constructed and arranged to draw all or a portion of the supply of air, at atmospheric temperature, through the layer 30 of material, after it has been thoroughly dried, thereby not only cooling said dried material but appreciably increasing the temperature of said air and correspondingly reducing the quantity of heat required for raising said air to the desired 35 initial temperature.

To effect the foregoing objects, my improved process and apparatus comprise the 45 various features, combinations of features and details of construction hereinafter described and claimed.

In the accompanying drawings, in which my invention is fully illustrated,

Figure 1 is a side view of the admission 50 end of a conveyer forming part of a drying apparatus of my invention adapted for the practice of my improved process.

Fig. 2 is a side view of a portion of said 55 conveyer intermediate its ends.

Fig. 3 is a side view of the discharge end

of said conveyer showing the machinery for driving the conveyer and other apparatus associated with said conveyer.

Fig. 4 is a sectional side view of the discharge end of the conveyer on the line 4—4 of Fig. 6.

Fig. 5 is a top plan view of a portion of said conveyer adjacent to its admission end.

Fig. 6 is a top plan view of a portion of said conveyer adjacent to its discharge end.

Fig. 7 is an end view of the admission end of said conveyer.

Fig. 8 is an enlarged fragmentary view 70 of a portion of the conveyer belt at the admission end of the conveyer.

Fig. 9 is a fragmentary top plan view of the conveyer belt from the position 9—9, Fig. 8; and

Fig. 10 is a fragmentary view of the machinery house showing an adjustable ventilator for admitting air to said machinery house.

In the accompanying drawings I have, for purpose of illustration, shown an apparatus for the practice of my improved process particularly designed and adapted for drying alfalfa and the like.

Said apparatus comprises a conveyer 85 designated, as a whole A, which comprises a trunk or casing B, preferably rectangular in cross section, and a conveyer belt C mounted within said trunk or casing and which extends lengthwise through the same. As shown, said conveyer belt C is of a familiar type comprising chain belts 1 and 2 at opposite sides of said conveyer belt, which are adjusted to sprocket wheels 3 and 4 rotatably mounted at the admission and discharge ends, respectively, of the trunk or casing B both the upper and lower laps of which are supported on track rails 5, 5', by means of brackets 6 secured to links of said chain belts at spaced intervals, said brackets having anti-friction rollers 7 mounted at the ends thereof which run upon said track rails 5, 5'.

Secured to the links of said chain belts 1 and 2 are slats 8, which form the supporting or carrying surface of said conveyer belt C. Where the chain belts 1 and 2 are spaced a considerable distance apart, as in apparatus for drying alfalfa and the like, said slats 8 are also preferably secured in proper spaced relation by means of a canvas belt 9 to which said slats 8 are bolted or riveted between the chain belts 1 and 2.

Said canvas belt 9 is adjusted to pulleys 10 and 11 rotatably mounted at the admission and discharge ends of the conveyer, corresponding to the sprocket wheels 3 and 4, respectively.

As shown the sprocket wheels 3 and pulleys 10 at the admission end of the conveyer are mounted on an idle shaft 12, while the sprocket wheels 4 and pulley 11 at the discharge end of the conveyer are secured to rotate with a shaft 13 which is adapted to be driven by means of driving connection with a suitable source of power, preferably through the medium of a variable speed device, in the manner presently described.

To provide for maintaining a desired tension on the conveyer belt C, the shaft 12 is mounted in suitable take-up boxes, indicated at c, c', mounted at the admission end 20 of the conveyer trunk or casing. Any desired or approved take-up device, of which several different kinds are available and may be purchased in the open market, may be used for this purpose and need not, therefore, be described in detail.

The conveyer trunk or casing B is preferably cut away for a considerable distance longitudinally thereof above the top lap of the conveyer belt C at both the admission 30 and discharge ends of said conveyer, thus exposing the carrying surface of said conveyer belt C and greatly facilitating depositing the material to be dried upon said conveyer belt at the admission end of the conveyer and its removal therefrom at the discharge end of the conveyer. In a machine for drying alfalfa and the like, which is of considerable length—a desirable size being about 150 feet from center to center 40 of the sprocket wheels 3 and 4—said casing B will preferably be cut away for from 14 to 16 feet at both its admission and discharge ends.

The trunk or casing B is preferably made 45 of sheet steel and is reinforced or strengthened by cleats or braces 14 secured thereto at intervals of a few feet throughout its length and, excepting as hereinafter particularly pointed out, the sides of said trunk or casing 50 are entirely closed. Also, to prevent excessive loss of heat from radiation, I contemplate covering the exterior of the conveyer trunk or casing B with a layer of asbestos or other suitable non-conductor of heat.

The conveyer A is supported upon a suitable foundation, consisting, preferably, of wood sills 15 which extend lengthwise of the conveyer trunk or casing B and which are preferably embedded in a concrete floor 60 b, the concrete imparting stability to the structure and the sills 15 affording convenient means for making attachments to said foundation.

Secured to the sides of the conveyer trunk 65 or casing B above the conveyer belt C and

projecting inwardly over the lateral edges of said conveyer belt and in close proximity to the upper surface thereof are guards 16. Said guards are preferably made of sheet metal and are inclined, forming, in effect 70 fillets which close the spaces between the lateral edges of the conveyer belt C and the sides of the conveyer trunk or casing B, thus preventing the conveyed material from falling through said spaces.

The front or admission end of the conveyer trunk or casing B above the conveyer belt C is open and the rear end thereof is closed preferably by means comprising a member which is freely movable toward 80 and from the conveyer belt C, gravity operating to maintain said member in contact with said conveyer belt or the material thereon, thus permitting said member to adjust itself automatically to varying thicknesses of the layer of material to be dried, supported on said conveyer belt. In the drawings, the line c² indicates the top of the layer of conveyed material.

As shown the closing means or closure for 90 the rear or discharge end of said conveyer comprises a drum 17 which is adapted to ride upon the exposed upper surface of the conveyer belt C or of the layer of material supported thereon, defined by the line c², and which is mounted to rotate freely in the ends of arms 18 pivoted at 19 to the outer sides of the conveyer trunk or casing B. The drum 17 is counter-balanced by means of counter-weights 20 on the arms 18, said 100 counter-weights being preferably adjustable lengthwise of said lever arms, thus providing for varying the pressure of said drum on the conveyer belt C and the material supported thereon, so that the weight of said drum shall not break or injure said conveyed material. The surface of said drum runs in close proximity to the surface of a segmental shield 21 secured in fixed position on the rear end of the trunk or casing 110 B, substantially concentric with the pivots 19 of the lever arms 18. Said shield 21 is continuous between the sides of the conveyer trunk or casing B and the ends of the drum 17 extend into close proximity to the sides of said trunk or casing. Attached to the shield 21, preferably adjacent to its upper edge, is a curtain 22 which depends at the front or inclosed side of the drum 17. The lower edge of said curtain is preferably weighted 115 and the air pressure within the conveyer trunk or casing will operate, in an obvious manner, to hold said curtain 22 in contact with the surface of the drum 17, thus effectively closing the space between said drum 120 and the shield 21 and also the rear or discharge end of the conveyer trunk or casing B above the conveyer belt C or the layer of material which may be supported thereon,

without interfering with the movement of 130

the conveyed material. As shown, slots 23, adapted to receive the ends of the shaft of the drum 17, are formed in the rear edges of the sides of the conveyer trunk or casing, 5 thus permitting free movement of said drum toward and from the conveyer belt C. Said drum 17 and shield 21 are preferably made of wood as light as consistent with requisite strength, and the surfaces thereof are covered with duck, canvas or the like to render them tight.

Also, to prevent the escape of air at the discharge end of the conveyer trunk or casing B, the space within said casing beneath 15 the upper lap of the conveyer belt C is shut off or closed by means of a transverse partition 24, preferably made of canvas, and which comprises separate sections spaced apart to form an opening for the passage of 20 the lower lap of the conveyer belt C, the edges of said partitions extending into close proximity to the upper surface of the lower lap of said conveyer belt and to the under surfaces of both the upper and lower laps 25 thereof.

The current of air passing through the conveyer trunk or casing B is caused to pass successively through the layer of material supported on the conveyer belt C by means 30 of transverse partitions 25 located above the conveyer belt C and other partitions 26 located beneath the upper lap of said conveyer belt, said partitions 25 being located intermediate the partitions 26 and being so 35 arranged that air entering said trunk or casing adjacent to its discharge end and below the upper lap of the conveyer belt will be caused to pass directly upward through the conveyer belt and the material supported 40 thereon.

Said partitions 25 and 26 are preferably made of canvas, the partitions 25 being made in the form of curtains and of such length that they will rest lightly on the upper surface of the conveyer belt when there is no material supported thereon, and the free lower edges thereof will be carried rearwardly by the material being conveyed, the lower edges of said curtains 25 being weighted 45 so that the current of air passing through the conveyer trunk or casing will not blow said curtain partitions with it, which would permit the current of air to pass freely through the trunk or casing above the upper 50 lap of the conveyer belt and the material conveyed thereby. The partitions 26 are fixed and are substantially similar to the partition 24 heretofore described, comprising separate sections spaced apart to form 55 openings in said partitions to permit the passage therethrough of the lower lap of the conveyer belt.

As preferably constructed, there will be four partitions below the conveyer belt C, 60 comprising the partition 24 in line with the

closed rear or discharge end of the conveyer trunk or casing, a partition 26 substantially in line with the inclosed front end of said conveyer trunk or casing, and two partitions 26 located substantially equidistant from 70 each other and from the end partitions 24 and 26. As shown, also, the partitions 25 are located equidistant between the end and intermediate partitions 24 and 26 at the under side of said conveyer belt. It will be 75 understood that the number of said deflecting partitions may be changed as desired and also their arrangement. For example, the hot air can equally well be admitted to the conveyer trunk or casing B above the 80 conveyer belt C and discharged therefrom either above or below said conveyer belt, as preferred. The necessary changes in arrangement of said partitions to cause the air passing through said conveyer trunk to 85 traverse any desired path, can readily be made by any skilled mechanic and need not, therefore, be described in detail.

To render the interior of the conveyer trunk or casing below the conveyer belt readily accessible, openings are formed at intervals in the sides of said trunk or casing, said openings being controlled by suitable closures, consisting, as shown, of slides 27, movably supported in suitable guides formed 95 on the said conveyer casing adjacent to the lateral edges of said openings.

As shown, the conveyer belt C is driven by means of suitable driving connection between the shaft 13 and the pulley of an 100 engine, indicated at D. As shown, said driving connection comprises a variable speed transmission, indicated at E, driven from the engine D by means of a belt d, a worm shaft F driven from said variable 105 speed transmission E by means of a chain belt e adjusted to sprocket wheels e¹, e² secured to rotate with the driving shaft of the transmission E and with the worm shaft F, respectively, and a worm f on said shaft F 110 which meshes with a worm wheel G secured to rotate with said shaft 13.

A desirable form of variable speed transmission E is that known to the trade as a Reeves Class "A" variable speed transmission, but any desired form of transmission 115 may be used.

Preferably, also, the sprocket wheel e² for driving the worm shaft F is adapted to be secured to and disconnected from said worm shaft by means of a suitable clutch, which may be of any usual or approved form and which provides for quickly and conveniently starting and stopping the conveyer belt C.

A circulation of hot air is maintained 125 through the trunk or casing B of the conveyer by means of a fan indicated at H, which, as shown, is driven directly from the engine D, the current of air delivered into said trunk or casing B from said fan being 130

heated by means of a suitable heater indicated at I, from which the air passes directly into the trunk or casing B closely adjacent to its discharge end. As shown, 5 said heater is of the familiar type comprising series of steam pipes or coils inclosed in a suitable casing provided with an admission opening which communicates with the discharge opening of the fan H, and with a discharge opening which communicates with a 10 suitable hole i or opening formed in the side wall of the conveyer trunk or casing B below the upper lap of the conveyer belt C.

In accordance with my improved process 15 of drying materials, the air supplied to the fan H is drawn wholly or in part through the section of the conveyer belt C which is exposed at the rear or discharge end of the conveyer beyond the end of the trunk or 20 casing B and also through any material which may be contained thereon. This air being of the same temperature as the atmosphere and cold as compared with the current of air delivered into the conveyer 25 trunk or casing B, will operate, in an obvious manner, to cool the material contained on said section of the conveyer belt. Also, said material being hot, will operate to heat the air supplied to the blower and thence 30 to the conveyer trunk or casing B, thus effecting a material saving in fuel necessary for heating said air.

It is obvious that the extent to which the material on which the drier is operating at 35 a given time will be cooled and the air drawn through said material will be heated, will depend directly upon the rate of travel of the conveyer belt C, the material being more thoroughly cooled and the air heated to a 40 higher degree as said conveyer belt travels more slowly and the cooling of the material and the heating of the air decreasing as the rate of movement of the conveyer belt increases. Regardless of the material undergoing treatment, said conveyer belt is driven 45 at such speed that when the conveyed material, after passing through the conveyer trunk or casing B reaches the extreme rear or discharge end of the conveyer belt C it 50 will be cooled to such an extent that it can at once be packed for shipment and sale.

In the case of alfalfa, for drying which the apparatus shown in the drawings is particularly designed and adapted, the movement of the conveyer belt C is adjusted to 55 such a speed that it will require approximately from 30 minutes to 2 hours for the material to pass through said conveyer, depending upon the initial amount of moisture 60 in the green product, the depth of the material on the conveyer belt, and the temperature of the air.

My invention contemplates connecting the suction side of the blower H with the inclosed space beneath the exposed section of

the conveyer belt C at the discharge end of the conveyer. Simple means for this purpose, which will also serve to protect the engine, blower, heater etc., from the elements, consists in inclosing said engine, 70 blower, heater and associated devices in a house, which is substantially air-tight excepting that it communicates directly with the space beneath the exposed section of the discharge end of the conveyer belt by means 75 of suitable holes or openings formed in the side wall of the trunk or casing which incloses said space, and, where only part of the air supply for the fan or blower is to be drawn through the exposed rear end of 80 the conveyer and the layer of material thereon, said house may be provided with an opening for admitting air directly thereto from the atmosphere, said opening being preferably provided and controlled by 85 means of a suitable form of damper, by means of which the relative quantities of air admitted to the house through said opening and through the conveyer belt and the material supported thereon may be regulated as desired.

In the drawing said house is indicated by the dotted lines J, and the regulating damper at j.

My improved process and apparatus 95 possesses many and very important advantages over the usual process of sun drying or curing. In the case of hay or alfalfa, for instance, the proper sun curing of said hay depends entirely upon the weather, and even with fine weather results in very materially bleaching the hay or alfalfa, and in case of rain or dew after said hay or alfalfa has been partially dried, results not only in further bleaching the hay or alfalfa, but also extracts therefrom a very considerable part of its food properties. Moreover, the handling of the hay in the fields when dried, results in a very considerable percentage of loss, varying from 15% as a minimum to upwards of 25%.

With my improved process and apparatus, however, hay, alfalfa and the like, and other similar products may be cut at any time regardless of the weather, and even in wet 115 weather, as the drying thereof is in no way dependent upon the weather; dried by means of my improved process and in my improved apparatus, they are practically not bleached at all, but, when dried, retain their natural 120 colors; they retain practically all of their food properties; and there is practically no shrinkage or loss in handling, as the hay and alfalfa are handled green prior to being delivered to the drying apparatus and everything deposited upon the admission end of the conveyer belt is delivered at the discharge end thereof.

It will be observed also that with my apparatus and method, I can approximate 130

ideal conditions, namely, complete saturation of the air at the exit end of the tunnel as well as a gradual reduction of the temperature of the air, without reheating at any 5 point along the tunnel, so that by the time the air makes its exit its entire caloric value has been approximately obtained.

I claim.

1. The process of drying materials which 10 consists in feeding a layer of material to be dried, passing a current of air moving in a reverse direction to said layer of material to be dried, heated to a desired relatively high initial temperature, repeatedly alternately up and down through said layer of 15 material without reheating, thereby causing said current of air to gradually fall by successive passages through said layer of material to a desired relatively low temperature at the 20 point of supply of the material to be dried, whereby the material to be dried will be subjected to an initial relatively low temperature and to a gradually increasing temperature as the liquid content thereof 25 decreases, and attaining a desired maximum temperature when the liquid content thereof is reduced to a desired minimum, substantially as described.

2. The process of drying materials which 30 consists in feeding a layer of material to be dried through a trunk, passing a current of air under pressure moving through said trunk in a reverse direction to said layer of material to be dried, heated to a desired relatively high initial temperature, repeatedly alternately up and down through said 35 layer of material without reheating, thereby causing said current of air to gradually fall by successive passages through said layer of 40 material to a desired relatively low temperature at the point of supply of the material to be dried, whereby the material to be dried will be subjected to an initial relatively low temperature and to a gradually 45 increasing temperature as the liquid content thereof decreases, and attaining a desired maximum temperature when the liquid content thereof is reduced to a desired minimum, substantially as described.

3. The process of drying materials which 50 consists in feeding a layer of material to be dried, passing a current of air moving in a reverse direction to said layer of material repeatedly alternately up and down through 55 said layer of material, said current of air being relatively cold in its initial passage through said material to thereby cool the discharging dried material as well as initially heat the air, further heating said current 60 of air to a desired maximum temperature immediately subsequent to its initial passage through said material, and then permitting said current of air to traverse

said layer of material in the manner specified without reheating, whereby the temperature of the air will drop continuously until it is discharged at the point of supply of the fresh material.

4. In a drying apparatus, the combination 65 of a trunk or casing, a conveyer in said trunk or casing which extends lengthwise thereof and projects therefrom at its discharge end, means for closing the discharge end of said trunk or casing constructed and arranged to permit the passage of the conveyer and conveyed material, driving means 70 for said conveyer, means to create a current of air lengthwise through said trunk or casing in the reverse direction to the direction of movement of said conveyer, partitions within said casing above and below said conveyer constructed and arranged to cause said current of air to pass successively through said conveyer, means whereby the air is initially drawn through the section of 75 said conveyer at the discharge end of said trunk or casing which is outside thereof and which carries the hot dried product and thence forced into said trunk or casing adjacent to its discharge end, and means for 80 heating said current of air before it passes into said trunk or casing, substantially as described.

5. In a drying apparatus, the combination 85 of a trunk or casing, a conveyer in said trunk or casing which extends lengthwise thereof and projects therefrom at both ends, means for closing the discharge end of said trunk or casing constructed and arranged to permit the passage of the conveyer and 90 conveyed material, driving means for said conveyer, means to create a current of air lengthwise through said trunk or casing in the reverse direction to the direction of movement of said conveyer, partitions with 95 in said casing above and below said conveyer constructed and arranged to cause said current of air to pass successively through said conveyer, means whereby the air is initially drawn first through the section of 100 said conveyer at the discharge end of said trunk or casing which is outside thereof and which carries the hot dried product and thence forced into said trunk or casing adjacent to its discharge end, and means for 105 heating said current of air before it passes into said trunk or casing, substantially as described.

In testimony, that I claim the foregoing as my invention, I affix my signature in 110 presence of two subscribing witnesses this 3rd day of March A. D. 1916.

EDWIN M. BASSLER.
